UNITED STATES PATENT OFFICE.

ALBERT McDOWELL, OF NEW YORK, N. Y.

ADJUSTABLE PATTERN FOR DRAFTING TROUSERS.

SPECIFICATION forming part of Letters Patent No. 459,856, dated September 22, 1891.

Application filed May 6, 1891. Serial No. 391,844. (No model.)

To all whom it may concern.

Be it known that I, ALBERT McDOWELL, a citizen of the United States, and a resident of the city, county, and State of New York, have 5 invented certain Improvements in Adjustable Patterns for Drafting Garments, of which the following is a specification.

My invention relates to that class of patterns, usually of metal, which are made of 10 parts adjustably connected together, whereby the pattern may be set or adjusted to the measures taken and the parts then clamped together. When so set, the cloth or material or paper patterns may be outlined or marked 15 by following the outlines of the adjustable pattern. Such patterns are usually provided with scales whereby the parts may be adjusted.

The object of my present invention is to 20 provide a pattern of the above character for cutting out trousers from the usual measures taken by the tailor. A pair of trousers is made up in the main of two like or substantially like halves or divisions, each of which 25 consists of a front and back part, which are united at their edges by seams to form the leg portion, seat portion, and waist portion, and I provide an adjustable pattern for the said front part and another for the back part 30 two patterns only being required. After the measures have been taken in the usual way these patterns are set thereto and the parts clamped fast. It is only necessary then for the tailor or cutter to lay the patterns on the 35 goods and mark the outline of the same on the latter. The goods may then be cut along the line marked.

In the accompanying drawings, which 40 serve to illustrate two embodiments of my invention, Figure 1 is the part pattern for the front portion of the trousers, and Fig. 2 the part pattern for the back portion thereof. These views show an embodiment of the invention where the lateral expansion and contraction is on both sides of a central base-line. Figs. 3 and 4 are respectively similar 45 views illustrating an embodiment of the invention where the lateral expansion and contraction is nearly all at one side of a base-line.

My pattern will usually be made of sheet-

metal, but other materials may be used in its construction. The plates forming the outline where seams are required may be of the proper width to allow for the seam. The 55 outer margin, generally speaking, marks the cutting-line.

The several parts or plates of the pattern are connected together in three ways—namely, by rivets or integrally, which for convenience 60 I will characterize by the phrase “rigidly connected;” by a hinge, rivet, or stud to form a joint or articulation, which I will characterize as “hinged,” and by slots and rivets or screws, so that the plates are at liberty to 65 slide on each other for purposes of adjustment, which I will characterize simply as “connected.”

Referring to Fig. 1, which represents the part pattern for the front portion of the trousers, plates A¹, A², A³, and A⁴ form the longitudinal base-bar of the pattern, and plates A⁵, A⁶, A⁷, A⁸, A⁹, A¹⁰, A¹¹, and A¹² the transverse bars thereof. Plate A² is connected at its upper end to plate A¹ and at its lower end to plate 70 A³. Plate A³ is connected at its lower end to plate A⁴. These connected plates form a rigid base-bar, adjustable longitudinally at three points, and these adjustments are independent of each other and of the lateral or 75 transverse adjustments, to be hereinafter described. Plates A⁵ and A⁶ are connected together and to the plate A¹ and form the transverse waist-bar. Plates A⁷ and A⁸ are connected together and to plate A² to form the 80 transverse crotch or seat bar. Plates A⁹ and A¹⁰ are connected together and to plate A³ to form the transverse knee-bar, and plates A¹¹ and A¹² are connected together and to the plate A⁴ to form the transverse bottom bar. 85 The above-described connected plates form the skeleton or frame of the pattern, said bars being all extensible lengthwise and provided with scales for setting to measure and clamp-screws for securing them when properly set. 90 The adjustment of each transverse bar may be effected independently of that of the others and of the adjustments of the base-bar. The waist-bar and bottom bar also form parts 95 of the outline of the pattern. On the right-hand side of the pattern, as seen in Fig. 1, the plates A¹³, A¹⁴, A^{14x}, A¹⁵, A^{15x} and A¹⁶ form

the outline at the outside seam. Plate A¹³ is hinged to plate A⁶ at its upper end and connected to plate A¹⁴ at its lower end. Plate A¹⁴ and plate A^{14X} are hinged to plate A⁸, and plate A^{14X} is connected at its lower end to plate A¹⁵. Plate A¹⁵ and plate A^{15X} are hinged to plate A¹⁰, and plate A^{15X} is connected at its lower end to plate A¹⁶, and this latter plate is hinged at its lower end to plate A¹². On the left-hand side of Fig. 1 the plates A¹⁷, A¹⁸, A¹⁹, and A²⁰ form the outline at the fly on the front, and the plates A²¹, A^{21X}, A²², and A²³ form the outline of the inside seam of the leg. The plate A¹⁷ is hinged at its upper end to the plate A⁵, and at its lower end it is connected to the plate A¹⁸. The latter is connected at its lower end to the transverse plate A⁷ through the medium of a longitudinally-extending slot in the latter. The plates A¹⁹ and A²⁰ are curved and connected together, the former being hinged at its upper end to plate A¹⁸, and the plate A²⁰ being hinged at its lower end to an outwardly-projecting angle at the upper end of plate A²¹. This latter plate, which is broad at its upper part, is hinged at its inner angle to the outer end of the plate A⁷. The outer edge of plate A²¹ is curved, and it is connected at its lower end to the plate A^{21X}. This latter plate and plate A²² are hinged to the transverse plate A⁹, and plate A²² is connected at its lower end to plate A²³. The plate A²³ is hinged at its lower end to the transverse plate A¹¹. This construction permits the pattern to be expanded and contracted both laterally and longitudinally.

The pattern may be set to the measures as follows: The connected plates A³ and A⁴ are adjusted to the measure from the knee to the bottom of the leg by the graduated scale a on plate A⁴ and the plates are clamped together. The plates A² and A³ are adjusted to the measure from knee to crotch by the scale a' on plate A³ and the plates clamped fast. The plates A' and A² are adjusted to the measure from crotch to waist by the scale a² on plate A² and these plates clamped fast. These measures give the length. The width at the bottom of the leg is obtained by adjusting plates A¹¹ and A¹² to the scale a³ on plate A¹² and the plates clamped fast. The plates A⁹ and A¹⁰ are adjusted to the measure at the knee by the scale a⁴ on plate A¹⁰ and the plates clamped fast. The plates A⁷ and A⁸ are adjusted to the measure about the hips or seat by the scale a⁵ and the plates clamped fast, and the plates A⁵ and A⁶ are adjusted to the waist-measure by the scale a⁶ on plate A⁶ and these plates clamped fast. The plates at the sides of the pattern will adjust themselves automatically. The pattern thus adjusted is ready for use.

In order to effect the required adjustment at both sides of the central longitudinal base-bar formed of the plates A' to A⁴, I provide the pattern with four sets of links or spreading devices—one at the waist-bar, one at the crotch-bar, one at the knee-bar, and one at

the bottom bar. These devices consist each of a link or lever w, pivoted or hinged at its middle on the central longitudinal bar, and two links w', coupled to the respective ends of the link w at one end and to the respective ends of the transverse bar at their other ends. These sets of links are so clearly illustrated in Fig. 1 that they will require no further description.

The clamping of the sliding plates together may be effected by any suitable clamping devices. I prefer to employ clamping-screws x, one at each point of adjustment. The numerals of the several scales will of course be marked on the plates forming the pattern; but owing to the small scale of the drawings these numerals have been herein represented as at the sides of the several graduated plates.

Fig. 2 illustrates the part pattern for the back or rear portion of the trousers. This pattern will be constructed on substantially the same principles as that described. It will have a longitudinal base-bar composed of plates B', B², B³, and B⁴, and a crotch-bar, knee-bar, and bottom bar composed, respectively, of connected plates B⁷, B⁸, B⁹, B¹⁰, B¹¹, and B¹². The plates B², B³, and B⁴ will be provided, respectively, with scales b², b', and b, and the plates B⁸, B¹⁰, and B¹² will be provided, respectively, with scales b⁵, b⁴, and b³. The crotch-bar, knee-bar, and bottom bar will each be provided with a spreading device consisting of a lever w and links w', like the corresponding devices shown in Fig. 1 and hereinbefore described. The plates at the right-hand side of Fig. 2 and which correspond to the outside seam of the leg—namely, B¹³, B^{13X}, B¹⁴, B¹⁵, B^{15X}, and B¹⁶—will be joined or coupled in the same manner as the corresponding plates in Fig. 1. Plate B^{15X} may have a convex contour at y just below the knee, and plate B¹⁶ will have a salient contour at the bottom y'. The plates at the left-hand side of Fig. 2 from the crotch down and corresponding to the inside seam of the leg—namely, B²¹, B^{21X}, B²², and B²³—will be joined or coupled in the same manner as the corresponding parts in Fig. 1. Plate B²² may have a convex contour at y^X just below the knee, and plate B²³ will have a salient contour at the bottom y^X. The widening of the pattern at the bottom is to impart the “spring” to the bottom of the leg of the trousers. Above the crotch-bar this pattern differs somewhat in construction from that seen in Fig. 1. The plate B⁵ is rigidly connected to the plate B' and is arranged at right angles thereto. The plate B⁶ is connected to the plate B⁵ and hinged to the upper end of the plate B¹³. There is no scale on plate B⁶. The plate B¹⁷ is connected to the prolonged extremity of plate B⁵, which it crosses, the plate B⁵ being slotted at the connecting-point and provided with a scale b⁶. The plate B¹⁸ is connected to the lower end of plate B¹⁷, and at its lower end it is connected to plate B⁷ in the same manner that plate A¹⁸, Fig. 1, is connected to plate A⁷. The curved plates B¹⁹ and B²⁰

are arranged in the same way as the corresponding plates A¹⁹ and A²⁰ in Fig. 1. Above the plate B⁵ is an inclined waist-bar composed of plates B^x and B^{xx}. The plate B^x is hinged 5 to the plate B¹³ at the same point at which the plate B⁶ is hinged thereto. The plate B^{xx} is connected to the plate B^x, and at its other end it is connected to the upper part of the plate B¹⁷ above the plate B⁵. The plate B¹⁷ 10 has in it a longitudinal slot, and a clamp-screw on the plate B^{xx} plays in this slot.

In setting this pattern to the measures the longitudinal bar is set to the measures for length from waist to crotch, crotch to knee, 15 and knee to bottom, as before described with reference to Fig. 1, and transverse crotch-bar, knee-bar, and bottom-bar are also set to the respective measures, as set forth in the description of Fig. 1. The pattern is set to the 20 waist-measure by the scale b^{xx} on the plate B^{xx}, and the slope of the inclined bar is attained through the medium of the scale b¹⁷ on plate B¹⁷.

It will be seen that my pattern is composed 25 of two separate but interdependent parts, each provided with scales, whereby the pattern may be set to the measures taken by the tailor, and that each part is divided longitudinally from the crotch down into two extensible sections, 30 whereby the pattern may be set or adjusted to the measure from crotch to knee and from knee to bottom. It is also laterally extensible, so that it may be set or adjusted at the three points—namely, the crotch, knee, and 35 bottom—to the measures taken at these points. At the crotch a scale is provided for what is called the "body-depth." In Fig. 1 this scale a⁷ is seen on plate A⁷, the lower end of plate A¹⁸ being set to this scale, and in Fig. 2 this 40 scale b⁷ is seen on plate B⁷.

It is desirable to provide the pattern with two sets of scales, one adapted for use with the ordinary or actual measures taken by the tailor, as already described, and the other being 45 proportional scales for cutting out ready-made trousers to be kept in stock. For example, if the seat-measure be taken as the standard for proportion, and this measure in a particular case be thirty-six inches, then all 50 the proportional scales on the pattern will be set at the numeral 36, in order to cut a garment having the desired proportion. In Fig. 1 these proportional scales are indicated, respectively, by the letters e, e', e², e³, e⁴, and e⁶, 55 and in Fig. 2 they are indicated, respectively, by the letters g, g', g², g³, g⁴, g⁶, g^{xx}, and g¹⁷. There will be two scales on the crotch-bar by preference, one for the seat or hip measure, marked a⁵ in Fig. 1 and b⁵ in Fig. 2, and the 60 other for the hip-measure, marked a^{5x} in Fig. 1 and b^{5x} in Fig. 2. This will enable the tailor to set his pattern by either of these measures, as he may desire.

The construction of the pattern, as illustrated 65 in Figs. 3 and 4, differs from that already described in having the longitudinal base-bar arranged at one side or edge instead

of in the middle and in having the lateral adjustments nearly all at one side of said bar. Then the equalizing devices seen in Figs. 1 70 and 2 are dispensed with.

Fig. 3 is a part pattern for the front portion of the trousers and corresponds to the pattern seen in Fig. 1. At the left-hand side is a marginal base-bar corresponding to the fly 75 and the inside seam of the leg and comprising the plates C¹⁷, C¹⁸, C¹⁹, C²⁰, C^{20x}, C²¹, C²², and C²³. The transverse bars are formed of the following-named plates: The waist-bar of plates C⁵ and C⁶, the seat-bar of plates C⁷ and 80 C⁸, the knee-bar of plates C⁹ and C¹⁰, and the bottom bar of plates C¹¹ and C¹². The plate C¹⁷ is rigidly secured to the plate C⁵ at its upper end, and is connected at its other end to the plate C¹⁸. This latter plate is rigidly secured to the plate C⁷ at its lower end. The plate C²¹ is rigidly secured at its upper end to the plate C⁷, and is connected at its lower end to the plate C²². The plate C²² is rigidly secured to the plate C⁹, and is connected at 90 its lower end to plate C²³, which latter plate is rigidly secured to the plate C¹¹ of the bottom bar. The curved plates C¹⁹ and C²⁰ are connected together, and the plate C¹⁹ is hinged to the plate C¹⁸ at its upper end. At its lower 95 end the plate C²⁰ is connected to a slotted prolongation on the plate C⁷. The plate C^{20x} is also curved. It is connected to the plate C⁷ at the same point with plate C²⁰, and is connected through the medium of a slot in its 100 lower end with the plate C²¹. Of the transverse bars the two plates of which each bar is composed are connected together. The contour of the pattern at the right-hand side in Fig. 3, which corresponds to the outside 105 seam of the trousers, consists of the connected plates C¹³, C^{13x}, C¹⁴, C^{14x}, C¹⁵, and C¹⁶. Plate C¹³ is hinged to plate C⁶, plates C^{13x} and C¹⁴ are hinged to plate C⁸, plates C^{14x} and C¹⁵ are hinged to plate C¹⁰, and plate C¹⁶ is hinged to 110 plate C¹². The ordinary or actual measures of length are set on the scales c, c', and c² on the respective plates C²³, C²², and C¹⁸, and the transverse measures are set on the scales c³, c⁴, c⁵, and c⁶ on the respective plates C¹¹, C¹⁰, C⁸, 115 and C⁶. The measure of body-depth at the crotch is set on the scale c⁷ on plate C⁷, along which the clamp-screw x, which connects the plates C²⁰ and C^{20x} thereto, may be moved. On this pattern h, h', h², h³, h⁴, h⁶, and h⁷ are 120 the proportional scales before referred to in describing the patterns illustrated in Figs. 1 and 2.

Fig. 4 is the part pattern of the back portion of the trousers, said pattern corresponding 125 to the pattern illustrated in Fig. 2, except that as in Fig. 3 the lateral expansion and contraction is nearly all at one side and not equally on opposite sides of a central longitudinal base-bar. Above the crotch-bar the 130 construction is practically the same as in Fig. 2, and below the said bar it is substantially the same as the lower portion of the pattern in Fig. 3. Consequently only a brief description will

be needed. The longitudinal measurements are set on the base-bar, comprising the plates D³ and D⁴ above the crotch-bar and the plates D²¹, D²², and D²³ below said bar. These plates 5 constitute the longitudinal base-bar. The transverse bars are composed of the plates D^X, D^{XX}, D⁵, D⁶, D⁷, D⁸, D⁹, D¹⁰, D¹¹, and D¹². Plate D³ is rigidly connected to plate D⁵ and connected to the plate D⁴, and this latter plate 10 is rigidly connected at its lower end to plate D⁷. Plate D²¹ is rigidly connected to plate D⁷ and connected to plate D²². Plate D²² is rigidly connected to plate D⁹ and connected at its lower end to plate D²³. This latter plate 15 is rigidly connected to plate D¹¹. The waist-bar comprises the connected plates D⁵ and D⁶, the crotch-bar of the connected plates D⁷ and D⁸, the knee-bar of the connected plates D⁹ and D¹⁰, and the bottom bar of the connected 20 plates D¹¹ and D¹². The inclined bar above the waist-bar is composed of the connected plates D^X and D^{XX}. Plates D^{XX}, D⁶, D⁸, D¹⁰, and D¹² are hinged to the respective connected 25 plates D¹³, D^{13X}, D¹⁴, D¹⁵, D^{15X}, and D¹⁶, which form the outline at the outside seam of the trousers. The actual or ordinary measures 30 are set on the scale d, d', d², d³, d⁴, d⁵, d⁶, d⁷, d¹⁷, and d^X, and the proportional measures may be set on the scale i, i', i², i³, i⁴, i⁶, i⁷, i¹⁷, 35 and i^X. The thigh-measure may be set on the scale d^{5X} on the crotch-bar plate D⁸. The connected plates D¹⁷ and D¹⁸ are arranged the same as the corresponding plates in Fig. 2, and the curved plates D¹⁹, D²⁰, and D^{20X} are 40 arranged the same as the corresponding plates in Fig. 3.

The pairs of curved plates A¹⁹ A²⁰ in Fig. 1, B¹⁹ B²⁰ in Fig. 2, C¹⁹ C²⁰ in Fig. 3, and D¹⁹ D²⁰ in Fig. 4 perform the same function in all of 45 these part patterns, and this function is to regulate the depth of the body. Consequently the pair of plates is made adjustable at one end or the other toward and from the longitudinal base-bar or the axis of the part pattern. In 50 Figs. 1 and 2, for example, the pair of curved plates is adjustable at its upper end by the shifting of the plates A¹⁸ and B¹⁸, while in Fig. 3 it is adjustable at its lower end along the slot in the transverse plate C¹, the curved 55 plate C^{20X} being shifted simultaneously therewith.

By reason of the improvements herein described a pattern is provided which will hold its form or maintain its general contour when 55 unclamped and will at the same time allow of the necessary expansion or contraction in every direction and to the extent required for ordinary use. When set and clamped it will be rigid and afford a complete outline pattern, about which the tailor or fitter may run his chalk with perfect ease and with assurance of its correctness.

I do not wish to limit myself to the precise construction herein shown, as this may be 60 varied to some extent without departing materially from my invention.

The plates of which the pattern is composed may be of convenient width and of any suitable material.

The adjustable pattern is designed especially for use in drafting trousers and garments of a similar character, such as drawers, overalls, &c., and in drafting paper patterns for such garments.

Having thus described my invention, I claim—

1. A part pattern for drafting trousers and similar garments, composed of connected plates which slide on each other at the points of adjustment, and consisting of a centrally arranged, longitudinally-extensible, and rigid base-bar having three independently-extensible points of adjustment and scales at these points, transverse independently-extensible bars at the waist, crotch, knee, and bottom crossing and connected with said base-bar and each having a scale for setting it to measure, the outline or marginal plates and spreaders, one at each of said transverse bars, each spreader consisting of a lever pivotally attached at its middle to the base-bar, and links which couple the respective ends of said lever with the ends of the base-bar, as set forth.

2. The part pattern for drafting the front of the trousers, composed of connected plates which slide upon each other at the several points of adjustment, and consisting of the longitudinally-extensible base-bar, the extensible transverse bars which cross the base-bar and are connected therewith, the series of plates A²¹, A^{21X}, A²², and A²³, forming the outline for the inside seam, said series of plates being connected to the transverse bars, and the plates A¹⁷, A¹⁸, A¹⁹, and A²⁰, forming the 105 outline of the fly, said plates A¹⁷ and A¹⁸ being connected together, the former hinged to the waist-bar and the latter having a sliding connection with the crotch-bar, and the curved plates A¹⁹ and A²⁰ being connected together, 110 the former hinged to the plate A¹⁸ and the latter to the outline plate A²¹, as set forth.

3. In an adjustable part pattern for drafting the front of the trousers, the combination of the several plates connected together and arranged in the manner following, namely: the plates A¹, A², A³, and A⁴, which form the base-bar and slide on each other at the points of adjustment, the plates A⁵ and A⁶, which form the transverse waist-bar and slide on each other, the plates A⁷ and A⁸, which form the transverse crotch-bar and slide on each other, the plates A⁹ and A¹⁰, which form the transverse knee-bar and slide on each other, the plates A¹¹ and A¹², which form the transverse bottom bar and slide on each other, the plates A¹³, A¹⁴, A^{14X}, A¹⁵, A^{15X}, and A¹⁶, forming the outline at the outside seam, said plates sliding on each other where connected, and the series of plates hinged to the ends of the transverse bars, the plates A¹⁷ and A¹⁸, connected together and sliding on each other,

the plate A¹⁷ being hinged to the plate A⁵ and the plate A¹⁸ connected to the plate A⁷, the curved plates A¹⁹ and A²⁰, connected and sliding on each other, the plate A¹⁹ being 5 hinged to the plate A¹⁸ and the plate A²⁰ hinged to the plate A²¹, and the plates A²¹, A^{21^x}, A²², and A²³, which form the outline at the inside seam, connected and sliding on each other, said series of plates being hinged 10 to the transverse bars, substantially as set forth.

4. In an adjustable part pattern for the front of the trousers, the combination, with the transverse slotted plate A⁷, provided with 15 a scale a⁷, the exteriorly-curved plate A²¹, the transverse plate A⁵, and the plates A¹⁷ and A¹⁸, connected together, the former hinged to plate A⁵ and the latter connected to plate A⁷ at the said scale, of the connected curved plates 20 A¹⁹ and A²⁰, hinged at one end to plate A¹⁸ and at the other end to plate A²¹, said plates sliding upon each other where connected, substantially as set forth.

5. In an adjustable part pattern for the back 25 of the trousers, the combination of the connected plates B^x and B^{xx}, forming the inclined bar above the waist and sliding on each other, and the plates B¹⁷ and B¹⁸, forming the outline for the back seam and also sliding 30 on each other, the inclined bar having a slotted connection with said plate B¹⁷, substantially as set forth.

6. In an adjustable part pattern for the back 35 of the trousers, the combination of the connected plates B⁷ and B⁸, forming the extensible transverse crotch-bar, the connected plates B⁵ and B⁶, forming the extensible transverse waist-bar, the connected plates B¹ and B², which unite the said waist-bar and the 40 crotch-bar and form an extensible base-bar provided with a scale b², the connected outline-plates B¹⁸ and B^{18^x}, of which the former is hinged to the waist-bar and the latter to the crotch-bar, the connected outline-plates 45 B¹⁷ and B¹⁸, of which the former has a slotted connection with the plate B⁵ and the latter a like connection with the plate B⁷, the connected plates B^x and B^{xx}, of which the former is hinged to the plate B¹⁸ and the latter has a 50 slotted connection with the plate B¹⁷, the connected curved plates B¹⁹ and B²⁰, of which the former is hinged to the plate B¹⁸ and the latter to plate B²¹, and said plate B²¹, the adjustments being independent and the plates sliding 55 upon each other where connected.

7. An adjustable part pattern for drafting trousers, composed of connected plates, which slide upon each other at the several points of adjustment and having a pair of curved plates connected and sliding upon each other, 60 which plates form the outline at the crotch, said pair of connected plates being adjustable toward and from the longitudinal axis of the pattern at one extremity independently of the other adjustments of the pattern, for 65 the purpose of varying the depth of the body, as set forth.

8. In an adjustable part pattern for drafting the back of the trousers, the combination of the several plates connected together and 70 arranged in the manner following, namely: the plates B¹, B², B³, and B⁴, which form the base-bar and slide on each other at the points of adjustment, the plates B⁵ and B⁶, which form the transverse waist-bar and slide on 75 each other, the plates B⁷ and B⁸, which form the transverse crotch-bar and slide on each other, the plates B⁹ and B¹⁰, which form the transverse knee-bar and slide on each other, the plates B¹¹ and B¹², which form the trans- 80 verse bottom bar and slide on each other, the plates B¹³, B^{13^x}, B¹⁴, B¹⁵, B^{15^x}, and B¹⁶, forming the outline at the outside seam, said plates sliding on each other where connected and the series of plates hinged to the ends of the 85 transverse bars, the plates B¹⁷ and B¹⁸, connected and sliding on each other, the plate B¹⁷ having a slotted connection with plate B⁵ and the plate B¹⁸ having a slotted connection with plate B⁷, the plates B^x and B^{xx}, connected 90 and sliding on each other, the former hinged to plate B⁶ and the latter having a slotted connection with plate B¹⁷, the curved plates B¹⁹ and B²⁰, connected and sliding on each other, the former hinged to plate B¹⁸ and the 95 latter hinged to plate B²¹, and the plates B²¹, B^{21^x}, B²², and B²³, forming the outline at the inside seam, said plates being connected and sliding on each other where connected, and the series of plates being hinged to the trans- 100 verse bars, substantially as set forth.

In witness whereof I have hereunto signed my name in the presence of two subscribing witnesses.

ALBERT McDOWELL.
